UNITED STATES PATENT OFFICE.

GUSTAV A. KRUTTSCHNITT, OF NEWARK, NEW JERSEY.

DESIGN FOR A BOX OR RECEPTACLE.

SPECIFICATION forming part of Design No. 33,512, dated November 6, 1900.

Application filed October 8, 1900. Serial No. 32,454. Term of patent 3½ years.

To all whom it may concern:

Be it known that I, GUSTAV A. KRUTTSCHNITT, a citizen of the United States, residing at Newark, in the county of Essex and

5 State of New Jersey, have invented and produced a new and original Design for Boxes or Receptacles, of which the following is a specification, reference being had to the accompanying drawings, forming part thereof.

10 Figure 1 is a plan view of a box or receptacle, showing my design. Fig. 2 is a section through the lid or cover of the box on the line *x-x* of Fig. 1. Fig. 3 is a rear side view of the box. Fig. 4 is a side end view of the box.

15 The leading feature of my design consists of the border ornamentation along the outer portions of the substantially flat side walls and lid of the box, substantially as shown in the drawings.

20 In the drawings, B designates the lid or cover of the box A, which has a substantially flat face, as shown in Figs. 2, 3, and 4, and which face, as illustrated in Fig. 1, bears the ornamental border comprising the ornamen-

tal scroll-figure C and the inner defining border-line D. The scroll-figure C has the appearance of being in relief and as possessing a mottled surface.

The substantially flat side walls E of the box or receptacle similarly bear the same ornamental border, composed of the ornamental scroll-figure C and the inner defining border-line D, while the overlapping edges B' of the lid B bear the ornamental scroll-figure C.

The lid or cover B and the rear side wall 35 E' of the box further bear the ornamental hinges F.

What I claim is—

The design for a box or receptacle, as herein shown and described.

Signed at New York, in the county and State of New York, this 25th day of September, A. D. 1900.

GUSTAV A. KRUTTSCHNITT.
